UNITED STATES PATENT OFFICE.

ROSCOE B. DENGLER AND WILLIAM T. DENGLER, OF LEBANON, PENNSYLVANIA.

DESIGN FOR A BOTTLE.

Application filed June 1, 1925. Serial No. 18,626. Term of patent 3½ years.

To all whom it may concern:

Be it known that we, ROSCOE B. DENGLER and WILLIAM T. DENGLER, citizens of the United States, residing at Lebanon, in the county of Lebanon and State of Pennsylvania, have invented a new, original, and ornamental Design for a Bottle, of which the following is a specification, reference being had to the accompanying drawing, forming a part hereof.

We claim:
The ornamental design for a bottle, as shown.

ROSCOE B. DENGLER.
WILLIAM T. DENGLER.
